ATTORNEY

UNITED STATES PATENT OFFICE.

THEODORE E. GRIMM, OF NEWARK, NEW JERSEY, ASSIGNOR TO J. K. OSBORN MANUFACTURING COMPANY, OF HARRISON, NEW JERSEY, A CORPORATION OF NEW JERSEY.

BAG-FASTENER.

1,254,323.

Specification of Letters Patent. Patented Jan. 22, 1918.

Application filed May 29, 1917. Serial No. 171,677.

To all whom it may concern:

Be it known that I, THEODORE E. GRIMM, a citizen of the United States, residing in the city of Newark, in the county of Essex and State of New Jersey, have invented certain new and useful Improvements in Bag-Fasteners, of which the following is a full, clear, and exact description, such as will enable others skilled in the art to which it 10 pertains to make, construct, and use the same, reference being had to the accompanying drawings and to characters of reference marked thereon, forming a part of this specification.

15 My invention relates to bag fasteners, and more particularly to a type thereof applicable to bag frames having pivotally connected frame members, and embodying therein a lift latch adapted to lock said 20 frame members when closed. The jaws of the ordinary forms of hand bags, pocket-books, satchels, and the like, are all provided with interlocking members, such as lift-latches, balls or heads which spring or snap 25 past each other to hold the jaws together. If the hand bags or the like be unusually full or if either the projecting members constituting the fastener, or the jaws themselves, become bent or loosened, it often happens 30 that the jaws are accidentally opened and the contents of the bag are lost or abstracted without the knowledge of the owner.

35 My invention comprises a new and improved locking means for hand bags and the like, and by which I seek to overcome the objections found in those heretofore employed.

In order to eliminate the above-mentioned evils, and overcome these objections, I have 40 devised a new lock, which has all the advantages of manipulation of a center lock, and to combine with it the feature of locking the bag frame at two points, said lock being designed to co-act with the ordinary 45 lift lock for preventing accidental loosening or unfastening of the same.

The invention consists primarily in a bag 50 fastener embodying therein a frame consisting of hinged frame members, one of which has an opening in the top thereof, a lift latch member or knob provided with a lug adapted to project through said opening and within said frame, a spring, one portion of which is adapted to be operatively connected

with said lug, and another portion of which 55 is projected substantially radially of said lug and adapted to engage a side wall of said frame, and a nose or catch carried by the other frame member and adapted to be operatively connected by said lift member, 60 and a slidably secured locking device secured to the side of one of said frame members for engagement with the lift latch or catch member, said locking device being designed to co-act with the lift latch member 65 for preventing accidental loosening or unfastening of the same.

With the various objects of my present invention in view, the same consists in the novel bag frame fastener hereinafter set 70 forth; and, furthermore, this invention consists in the various arrangements and the parts thereof, all of which will be fully described in the accompanying specification and then finally embodied in the clauses of 75 the claim thereof, which are appended to and form an essential part of this specification.

* In the drawings,

Figure 1 represents a front elevation of 80 a bag frame, showing my improved fastener secured thereon.

Fig. 2 represents an edge elevation.

Figs. 3 and 4 represent respectively, an enlarged plan and a front elevation of the 85 chambered cap secured to one of the frame sections, the pull piece not being shown.

Fig. 5 represents an enlarged under plan view of one of the catch members.

Fig. 6 represents an enlarged vertical section of the frame members, taken on line 90 $a-a$ of Fig. 1, and looking in the direction indicated by the arrow.

Figs. 7 and 8 represent respectively, front 95 and side elevations of the locking bar; and

Figs. 9 and 10 represent similar views of the eccentric.

Similar characters of reference are shown in all of the above described views, to indicate corresponding parts.

Referring now to the drawings, 1 and 2 represent a pair of frame sections, which are pivotally connected at their lower end portions in the usual well-known manner. One 100 of said frame sections as 2 is provided in its upper surface with a suitably-arranged opening for the reception of an extension 105 3 formed on the catch member to be presently

- described, and the other frame section as 1, is provided with a suitable nosing or projection 4, or any other suitable means may be provided, designed to be brought into holding engagement with a suitable recess 5 or other means formed in the under side of the catch member, to firmly secure the bag frame sections or members in locked position.
- 10 The catch member 6 which may be of any desired form or configuration, consists of the closed casing, provided with a downwardly-projecting spring-holding member or extension 3, for the reception of the spring 8. The catch member 6 is further provided in its under side with another suitable recess 9, so that when the bag frame sections are closed, the locking member to be presently described, will be received into 20 said recess 9 and will co-act with the catch member to firmly secure the bag frame sections in locked position.

In my improved device, I provide a second locking device for holding the jaws together, which locking device is preferably secured to the frame member 1, and is operated independently of the catch member above described. In the specific form illustrated, I employ a chambered cap 10, and 30 a backing plate 11, the chambered cap 10 being secured to the frame member 1 by means of a pair of integral tongues 12 formed on the cap, which are inserted through recesses in the backing plate and 35 pass through suitable apertures formed on the frame member 1, and clenched over in any suitable or convenient manner.

Slidably secured within the chambered cap 10 and suitably guided therein by means 40 of a guide 13 formed in the top of said cap, is the locking member 14, one end of which is adapted to project outside of the chambered cap, and to engage with the recess 9 or other means formed in the underside of 45 the catch member and in close proximity to the recess 5, in order to have locking engagement therewith.

The locking member 14, as illustrated in 50 the drawings, is preferably made from a single piece of suitable sheet metal, and is provided with an aperture 15, designed to receive the eccentric 16. The eccentric 16 is also preferably made from a single piece of suitable sheet metal, and is provided with 55 a circular raised portion 17, designed to engage with and rotate in an aperture formed in the chambered cap 10. The circular raised portion 17 is further provided with an opening 18, to receive a loop 19, by means 60 of which a pull piece 20 is pivotally secured to the circular raised portion 17. In order to manipulate the eccentric 16, the ends of the loop 19 are clenched over on the under side of the circular raised portion 17, as 65 clearly indicated in the drawings. The

chambered cap 10, as clearly indicated in the drawings, is provided with a marginal flange 21, against which the backing plate 11 bears, in order to form a closed casing. The fastener just described serves for additionally holding the frame members 1 and 2 in locked position, and is independently operated from the catch member 6.

In order to operate my improved fastener, it is first necessary to turn the pull piece, 75 thereby causing the locking element 14, by means of the eccentric 16, to assume the position indicated in dotted lines in Fig. 2, in which case it is in locking engagement with the aperture 9 of the catch member 6. 80 In order to open the bag, the pull piece is again turned, when the locking member 14 returns to the position indicated in Figs. 4 and 6 of the drawings, thereby causing the locking element to become disengaged from 85 the aperture 9 of the catch member 6. If upward pressure is now brought to bear upon the casing by the thumb of the operator, the catch member 6 is swung backward on the spring holder member 3 and 90 out of locking engagement with the nosing or projection 4, causing the nosing 4 to clear the recess 5 therein.

Experience has demonstrated that the organization above described is a highly efficient one, and while the device described is the preferred embodiment of my present invention, I do not care to restrict myself to the exact details of construction, combination and arrangement herein set forth, it 95 being obvious that minor variations thereof, not involving the exercise of invention, may be made by any skilled mechanic, and such departures from what is herein described and claimed, not involving invention, I consider within the scope and terms of my 100 claims.

Having thus described my invention, what I desire to claim and secure by Letters Patent is:—

1. In combination, two frame members movable relatively to each other, a catch member carried by one of said frame members and having locking engagement with the other of said frame members, of a slidably secured locking device secured to the front of the other frame member for engagement with the under side of the said catch member.
2. In a lock for satchels, the combination 120 with a satchel having a catch member carried by one of the frame members for normally holding said satchel closed, of a locking member secured to the front of the other of said frame members, a chambered cap 125 mounted on said last-named frame member, a single locking member slidably secured within said cap, said locking member being further provided with an eccentric for operating the same to cause it to have locking 130

engagement with the under side of said catch member.

3. In combination, two frame members movable relatively to each other, a catch member carried by one of said frame members and having locking engagement with the other of said frame members, and a locking device slidably secured to the front of the other frame member for engagement 10 with the under side of the said catch member, said locking device comprising a cham- bered cap, a backing plate, an eccentric mounted to rotate in an aperture in said cap, a locking bar mounted upon said eccentric and means carried by said eccentric for operating said locking bar.

This specification signed and witnessed this 28th day of May, 1917.

THEODORE E. GRIMM.
